WINDOW SAFETY LOCK UNIT

Frederick J. Johanson, 23 Lanham Lane,
East Hartford, Conn. 06118

Filed Dec. 28, 1966, Ser. No. 5,210

Term of patent 14 years

(Cl. D50—5)

FIG. 1

FIG. 2

FIG. 3

FIG. 1 is a perspective view of a window safety lock unit embodying my new design.

FIG. 2 is a top plan view thereof.

FIG. 3 is a side elevational view thereof.

The broken line representation of a portion of a double-hung window is for purposes of illustration only.

I claim:

The ornamental design for a window safety lock unit, as shown and described.
